UNITED STATES PATENT OFFICE.

ELI REESE, OF MAHANOY CITY, PENNSYLVANIA.

IMPROVEMENT IN STEAM PUMPS AND CONDENSERS.

Specification forming part of Letters Patent No. 137,796, dated April 15, 1873; application filed February 5, 1873.

To all whom it may concern:

Be it known that I, ELI REESE, of Mahanoy City, in the county of Schuylkill and State of Pennsylvania, have invented certain new and useful Improvements in Steam-Pump Condenser; and I do hereby declare that the following is a full, clear, and exact description thereof, reference being had to the accompanying drawing and to the letters of reference marked thereon which form a part of this specification.

My invention relates to the steam-pump and condenser for which Letters Patent were granted to me in 1872; and it consists in condensing the exhaust steam from the cylinder of steam-pumps with water partly from the column of discharge-pipes and partly with water from the suction-pipes, giving the pump the benefit of the water so lifted by the vacuum formed in the condenser, and assisting the pressure in the steam-cylinder by having a vacuum on the opposite side of the piston, and, also, by this means of using up all exhaust steam, does away with injury to timbers, &c., in the mines.

In order to enable others skilled in the art to which my invention appertains to make and use the same, I will now proceed to describe its construction and operation, referring to the annexed drawing, in which—

Figure 1 is a perspective view, and Fig. 2 a vertical section, of my condenser.

A represents the cylinder, which constitutes the condenser, and into which the exhaust steam passes from the steam-cylinder through the pipe B on top. C is a small cock with perforated pipe, which is attached to the column of discharge-pipes and enters the cylinder on the side near the top. D is the suc-

tion-pipe attached to the cylinder at or near the top, and provided with check-valve, perforated pipe, elbow, and cock, and connects with the well. The pipes E E, with check-valves, cocks, &c., attached to the bottom of the condenser connect to the pump, and, as shown, are arranged for two single or one double acting pump. The pipe G attached to the cylinder at about the center, with T-piece, elbow, check, and cock, are for the purpose of blowing through so as to form a vacuum in the first place, and a vacuum-gage is put in the elbow to ascertain the amount of vacuum.

The operation is as follows: The steam is exhausted into the condenser through the top pipe B; then the water from the side cock C, being discharged in, starts to form a vacuum by the condensation of the steam, and the suction-water commences to flow in and completes the vacuum and fills the condenser with water.

The steam-pump, being in motion, draws the water so filled in the condenser into the working-barrel, and on the return stroke discharges it into column pipes, and so continues.

Having thus fully described my invention, what I claim as new, and desire to secure by Letters Patent, is—

The condenser A; exhaust-steam inlet B, spray-discharge pipe C, blow-pipe G, suction-pipe D, and pump connecting-pipes E E, all constructed and arranged for operation as and for the purpose specified.

In testimony that I claim the foregoing as my own I affix my signature in presence of two witnesses.

ELI REESE.
